POURING AND STORING CONTAINER

Llewellyn W. Evans and Arthur L. Hamilton,
Richmond, Calif., assignors to Rheem Manufacturing Company, Richmond, Calif., a corporation of California

Application July 29, 1935, Serial No. 33,686

8 Claims. (Cl. 221—28)

Our invention relates to metal containers, such as pails, cans and drums, arranged for containing liquids, and having at the top or side thereof a spout for facilitating pouring of the liquid from the container.

An object of the invention is to provide the container with an extendible spout which may be projected to a considerable distance from the container proper, yet need not be retracted or backed into the contents of the container when not in use.

Another object of the invention is to provide an extendible pouring spout which will permit discharging of the contents from the container, both in the extended and in the retracted positions of the spout, and regardless of the amount of liquid remaining in the container.

A further object of the invention is to provide a spout which may be extended from the container in different curved and angular positions.

A still further object of the invention is to provide a device of the character described, in which all of the parts of the spout and the appurtenances thereof, including a means of insuring the admission of air to the container during the pouring operation, may be combined and assembled in the form of a single unit and applied as such to the container walls.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

40 Figure 1 is an enlarged longitudinal sectional view of the spout unit as applied to a container wall and showing the spout in an extended position for normal use.

45 Figure 2 is a view similar to Figure 1 but showing the spout retracted and covered.

Figure 3 is a side view of a portion of a container, with parts broken away to show the spout unit.

Figure 4 is a plan view of the container and unit as shown in Figure 3.

Figure 5 is a sectional view similar to Figure 2, but showing the unit as applied to a different form of container head.

Figure 6 is a bottom view of the unit as detached from the container wall.

Figure 7 is a sectional view of a unit of somewhat modified design.

As illustrated in the drawings, the spout unit 2 is applied to a head 3 which forms part of a container 4 and has formed therein a discharge opening 6 about which the unit is disposed. In the embodiment of the invention illustrated in Figures 1 to 4, the head is formed with a diametrically extending upset portion 7 containing the opening 6 and defining on the inner side of the head an inverted channel 8 which gradually decreases in width from a point adjacent one edge of the head and where the opening 6 is located, to a point at or adjacent the opposite edge of the head.

The spout unit, as here shown, is made up with what may be termed inner and outer necks 9 and 10 arranged in concentric relation and in registration with the opening 6. The necks are formed with base portions each designed for fixed connection with the head, and desirably the base 12 of the inner neck and the base 13 of the outer neck are arranged to be secured together and applied to the head as a unit. In the present form of the invention, a ring 14 is made part of the unit and such ring holds the base 12 against the base 13 and forms with the latter the flange of the unit wherewith the cooperating flange 16 of the head is interlocked to provide an effective seamed joint.

The inner neck is arranged to provide an extendible spout and is formed of a plurality of tubular sections 17 of which the base 12 may be considered one section. The sections are formed progressively one of smaller diameter than the other so that one may nest within another and each is tapered or otherwise formed so that the sections may be extended one from the other to an appreciable though limited extent, and when so extended the joints between the sections will be substantially liquid-tight and the outermost section 17 may be disposed considerably outward from the base section 12 and with its outlet orifice well advanced beyond the rim 18 of the container. The sections may be made progressively smaller in diameter from the section 12 to the section 17' and thus arranged to surround the section 12 and when retracted or collapsed to lie in the space between the inner and outer necks 9 and 10, or as here shown, in order to permit greater facility in manipulation, the diameter of the sections decrease from the section 12 to section 17' to lie within the opening defined by the section 12. In keeping with the latter arrangement, the ring member 14 has a portion 19 which

extends partly into the opening 6 and provides a stop or support for the sections when the latter are retracted one within the other, or in other words when the spout is in collapsed position. 5 Desirably the ring portion 19 is perforated or otherwise formed so that the free flow of the contents through the opening 6 will not be interfered with or the capacity of such opening restricted.

A full lip 20 is provided along the outer rim of 10 the section 17' so as to facilitate pouring of liquid from the spout without spilling or running backward along the sides of the latter. Preferably the lip 20 is made large enough to project over and cover all of the other sections when the spout is 15 collapsed as indicated in Figure 2. Furthermore, the sections are preferably so formed and designed, that when in retracted position, the outer end of each of them will lie inwardly of the outer end of the outer neck 10, and thus when the sections are so disposed they will be completely 20 shielded by said neck. A cap, 22, may be positioned on and engaged with the end 21 when the spout is collapsed, so as to close the opening 6 and seal the container thereat.

It is important to note that with the device of 25 our invention, no portion is required to protrude into the interior of the container, either in the extended or retracted positions of the spout. In this way, regardless of the amount of liquid in the container or the position in which the container is held during the pouring operation, the free flow of the liquid from the container will in no manner be interfered with. Furthermore, regardless of the depth of the container, the spout 30 may be constructed so as to extend outwardly from the container head practically any amount desired. It is to be also noted that the portion of the base section 12 between the point of attachment of the head and the innermost point of engagement of such section and the next section 35 40 when the latter is in extended position, is formed in a smooth curve from which the wall of said next section may extend in tangential relation. It will thus be clear that when the sections are extended as indicated in Figure 1, the liquid 45 from the container may flow smoothly and easily into and through the spout. Of importance also is the fact that since the lower section 12 is formed as a fixed part of the container and extends outward therefrom to an appreciable degree, the 50 smooth and free flow of the liquid can under some circumstances be permitted without extending the sections.

A feature of considerable advantage which arises out of the sectional design and of the manner of connection of the sections, is the flexible nature of the spout when in extended position. 55 By reason of this construction not only may the spout be extended in different angular relations to the head, but the spout may be extended in a 60 curve so as to position the spout discharge orifice as defined by the lip 20 in considerable angular relation to the orifice 6 and well over the outer neck 10.

Preferably included as a part of the spout unit 65 and arranged for application as such to the container head, is a means insuring the flow of air to the interior of the container as the liquid is being poured from the spout. As will be clear from Figures 1 and 2, the outer neck 10 and the base section 12 of the inner neck are spaced to define an annular chamber 26 which by means of an opening 27 at the bottom thereof is afforded communication with the interior of the container. In order that the chamber may have communication with the uppermost portion of the interior

of the container, such as when the latter is tilted during the pouring operation, an air pipe 28 is extended from the chamber at the opening 27 to a point at the top of the container interior, the portion of the side wall of the container 5 diametrically opposite the opening 6. For the operative connection and attachment of the pipe to the spout unit, the portions of the base 12 and the ring 14 at the opening 27 are offset and the ring is formed with a laterally extending socket 29 10 in which one end of the pipe is firmly but desirably removably held. It will be understood that during the pouring operation, the chamber 26 is uncovered, and therefore the air may flow freely thereto and into the pipe during said 15 operation. No restriction of the discharge opening 6 is entailed, and when the cap is positioned over the unit as in Figure 2, the opening 27 as well as opening 6, is closed and sealed. It will be noted that the channel 8 provides a shielded cavity 20 for the reception of the air pipe.

In the form of the invention, illustrated in Figure 5, the unit is simply positioned on the container head with axis of the discharge opening 6 and of the spout unit perpendicular to the plane 25 of the head. This arrangement avoids the use of the diametrically extending offset in the head, and any desired inclination or curvature in the spout for insuring ready pouring over the rim of the container is effected by flexing the spout 30 through appropriate relative positioning of the sections.

In Figure 7, a modified form of closing and sealing means is provided for the spout unit. As here shown, the upper portion of the outer neck 35 10 is extended to provide an integral cap or closure 31 which together with such neck forms a complete and sealed enclosure for the inner neck including the spout sections. The closure portion 31 is connected to the neck by a weakened 40 marginal portion 32, and when the spout is put into initial use the portion 31 may be readily severed from the remainder of the neck so that the spout sections can be withdrawn and extended from the enclosing neck portion 12. Desirably the cap portion 31 in its position before 45 removal from the neck, lies depressed below and inwardly of the rim of the latter so that upon the subsequent removal of the cap portion the rim will remain smooth on the inner side of the neck. 50 A cover 33, designed for threaded engagement with the neck, is provided for closing and sealing the opening in the neck when the cap portion 31 has been removed.

We claim:

1. The combination with a container having a discharge opening, of an extendible neck surrounding said opening and formed with a plurality of tubular sections retractible one within another, means to support the individual sections 60 for relative rotation at the opening while in retracted position, a collar fixed to the container and surrounding said sections in spaced relation to the opening, a complete annular pouring lip on the outer of said sections positioned to lie 65 inwardly of the outer extremity of the collar when the sections are in retracted position, and a closure cap for the collar.

2. The combination with a container having a head with an upset portion extending diametrically thereacross and defining an inverted channel on the underside of the head, said head having a discharge opening adjacent one side of the container and disposed with its axis in oblique relation to the longitudinal axis of the container, 70

of a pouring spout comprising telescopic sections operatively connected with said head in surrounding relation to said opening, an enclosure connected with said head and surrounding said

5 sections and defining therewith an air chamber, a conduit operatively connecting said chamber with the interior of said container at a point immediately under said head and diametrically opposite said side of the container, and a removable 10 cover for said enclosure.

3. The combination with a metal container having a head depressed below the upper edge of the sides of the container and provided adjacent one side with an opening, of a combined closure

15 and pouring unit comprising an inner tubular member formed with telescoping sections to provide a pouring spout extendible toward and above said edge, an outer tubular member surrounding said inner member in at least partly spaced relation

20 to promote an air chamber therebetween, a ring member for supporting said sections in a retractable position and cooperating with said first members in securing the unit to said head with the axis of the unit substantially perpendicularly to said head, a conduit extending from said chamber and along the under side of said head, and a closure for said outer member.

25 4. The combination with a metal container having a head, of a combined closure and pouring unit comprising an inner tubular member formed with telescoping sections to provide a pouring

30 spout, an outer tubular member surrounding said inner member in at least partly spaced relation to provide an air chamber therebetween, means for supporting said sections in a retractable position, a conduit extending from said chamber and along the under side of said head, and a closure for said outer member.

35 5. The combination with a metal container having a head, of a combined closure and pouring unit comprising an inner tubular member formed with telescoping sections to provide a pouring spout, an outer tubular member surrounding said inner member in at least partly spaced relation to provide an air chamber therebetween, a ring member for supporting said sections in a

retractable position and cooperating with said first members in securing the unit to said head, a conduit extending from said chamber and along the under side of said head, and a closure for said outer member.

5 6. In combination with a container having a head with a discharge opening, of an enclosure extending from said head around said opening, a spout having an extendible portion positioned within said enclosure and arranged in all of its 10 positions to form with said enclosure a chamber, and a conduit within said container extending from said chamber to adjacent a side wall of the container.

7. A combined pouring and closure unit for 15 a container having a wall with a discharge opening therein, comprising an extendible multi-sectioned spout having a fixed section extending from said head about said opening and being of gradually increasing cross-sectional area where- 20 by the walls of said section will provide a guide for smoothly directing the contents of the container into another section of the spout, an enclosure member extending around said spout in fixed spaced relation to the sides thereof, and a 25 conduit providing for the passage of air between the interior and exterior of the container by way of the space between the spout and enclosure member.

30 8. A pouring and closure unit for a container having a discharge opening in a wall thereof, comprising inner and outer tubular members spaced to provide an annular chamber therebetween and joined at one end to close said chamber thereat, one of said members having an aperture at said end of the chamber, and a conduit for communicating the interior of the container with the atmosphere at the exterior thereof and having an end extending to said aperture, an extendible spout member slidably carried by said 40 inner member, said inner and spout members having complementary coengaging tapered bearing surfaces serving to limit the outward extension of said spout in the inner member.
